UNITED STATES PATENT OFFICE

DELORE J. BENOIT, OF FORDSON, MICHIGAN

COMBINATION DOOR

Application filed October 16, 1929. Serial No. 399,914.

This invention relates to combination doors, and the object is to provide a door which is convertible to a door having the appearance of the usual wood paneled door, a half screen 5 door, or a door having louvres in its upper portion.

A feature of the invention is in the provision of a frame member adapted to be introduced and secured between the stiles and the 10 upper cross piece of a door, taking the place of the usual panels thereof, and provided with movable panels in its upper portion, a pocket in the lower portion thereof to receive the said panels, and a stationary screen member in the upper portion of the door lying between the movable panels when in closed position.

It is therefore an object of the invention to provide an insertible frame for use with an 20 ordinary door by removal of the lower stile and panels and of such character that, when secured to the stiles and cross member, the door frame is strengthened providing a rigid combination or convertible door that may be 25 utilized in any of the various ways enumerated.

A further feature of the invention is in the provision of an insertible metal frame having 30 side members and lower cross pieces attachable to the stiles and upper cross pieces of the door and tying the same together and either of a solid metal frame construction having grooves for the various panels whereby they are held and guided in their movement, the 35 lower cross piece of the metal frame being slotted to permit introduction of the panels subsequent to the securing of the metal frame to the stiles and head piece of the door.

These and other various objects and novel 40 features of the invention are hereinafter more fully described and claimed, and the preferred form of construction of a convertible door embodying my invention is shown in the accompanying drawings in which—

45 Fig. 1 is a general elevation of a door shown

in dotted lines in which my insertible combination door shown in full lines is mounted.

Fig. 2 is a sectional view of the upper portion of the insertible portion of the door with the panels moved downwardly exposing the 50 screen member to view.

Fig. 3 is a view similar to Fig. 1 showing the louvre panel positioned to cover the upper section of the door.

Fig. 4 is a longitudinal section of the 55 insertible portion of the door taken on line 4—4 of Fig. 1 showing the hollow metal frame construction.

Fig. 5 is an enlarged sectional view on line 5—5 of Fig. 1.

Fig. 6 is an enlarged sectional view on line 6—6 of Fig. 1.

Fig. 7 is an elevation of an alternative form of construction showing the door member with the insertible metal frame and panels in 65 place, the frame being of a solid construction.

Fig. 8 is a section taken on line 8—8 of Fig. 7.

Fig. 9 is a section taken on line 9—9 of Fig. 1.

Fig. 10 is a section taken on line 10—10 of Fig. 7.

Fig. 11 is a perspective detail showing the means for supporting the screen member in 75 place.

It is first to be observed that primarily the invention comprises the use of a metal frame member 1 shown in Fig. 1 having vertical side members and upper and lower cross members carrying movable and stationary panels and 80 insertible in the door in place of the usual glass or wood panels. As shown in Fig. 4, the frames may be of hollow metal form and such construction. There is also preferably provided a cross member 2 intermediate the 85 top and bottom cross members and extending between the two opposite vertical side members of the inserted frame 1 and secured thereto or formed in continuity with the lower stationary panel sections 3 and 4 on opposite 90

sides as shown in Fig. 4. Thus, the lower or stationary panels and the cross members 2 upon the opposite sides provide a hollow recess or pocket 5 into which the movable panels 6 and 7 may be retracted. These movable panels 6 and 7 have their edges riding in grooves provided therefor by securing open channel members 8 to the inner face of the vertical frames which guide the same in their movement. As may be seen from Fig. 3 one of the side members of the insertable frame is apertured in its opposite side faces to receive a shaft 9 at the outer end of which is secured an operating handle 10. On this shaft is a pair of gears 11 and 12 having the flanger side faces 13 and 14 in each instance and the edges of the panels 6 and 7 lie between these side flanges 13 and 14 of the respective gears.

The edges of the panels are toothed at 15 to provide racks meshing with the gears and by rotation of the handle 10 the two panels 6 and 7 may be raised to the position shown in Fig. 4 providing a door having the usual imperforate panels or they may be retracted 25 into the pocket 5 provided in the lower part of the door between the side plates 3 and 4.

There is a screen member 16 fixed in position in the upper section of the door extending from the upper cross member 17 of 30 the door to between the cross members 2 thereof there being channels 18 or other means provided for securing the screen member in position. As this screen member is fixed in place, on lowering the movable 35 panels 6 and 7 the ordinary screen door is provided so far as the upper section of the door is concerned.

It is oftentimes desirable to provide for ventilation and therefore these panels 6 and 40 7 may be moved downwardly into the recess provided therein leaving the upper section of the door with a screen. It is also sometimes desirable to secure ventilation and prevent others from looking into a room and 45 for this purpose I provide a third movable panel 19 which is provided with a series of louvres 20 preferably being formed of sheet metal and the louvres stamped thereinto as is the usual method in forming such a panel 50 member. This louvre panel rides in channels provided therefor as with the gear operated panels as indicated at 21 in Fig. 5 and 22 on the opposite sides of Fig. 6.

The channel 21 is supported at the upper 55 and lower ends and is not mounted on the side frame as is the case with the opposite channel 22. This is to enable a louvre 19 to be moved upwardly and downwardly past the shaft 9 heretofore described.

60 This louvre 19 is to be manually operated as by means of an eye 23 at its upper edge which permits the operator to lift the louvre to the position shown in Fig. 3. It may there be held in place as by means of a hook 24 secured to the upper cross piece of the in-

sertible frame. By moving the louvre to the position shown in Fig. 3 ventilation is secured without possibility of persons looking directly into a room through the screen member.

The preferred form of the structure is shown in Figs. 9 to 11 inclusive and consists of a metal frame of rectangular form having the two side members 30 and top cross member 31 and the lower cross member 32. 70 The side pieces 30 and the cross member 31 are grooved as shown in Fig. 8 to receive the two outer panels 33 and 34 on opposite faces of the door and grooves are also provided to receive the movable solid panels 35 and 36 and a groove 37 to receive the louvre panel 38 on one side of the stationary screen member 39 and a groove 40 in which the louvre member may be placed when it is desired to position the louvre on the opposite side of the screen. In this latter form of construction the screen frame 41 is secured by means of screws to a flange 43 extending through a slot in the frame 30 and secured therein by a screw 44 as shown in Fig. 8.

By this arrangement the screen frame 41, which is secured to the flange 43 which extends inwardly from the side frames 30 of the upper portion of the door and from the cross frame 31, may be removed by removal of the fastening screws and thus a repair or new screen may be readily secured therein. As in the previous case of the hollow frame first described it is therefore to be seen that the screen member is stationarily positioned 95 extending across the upper portion of the door above the stationary panels 33 and 34. The louvre 38 is arranged similarly as in the construction above described and is manually movable and secured in place as in the previous instance.

For the purpose of operating the two movable panels 35 and 36 (Fig. 10) the shaft 45 and gears 46 and 47 thereon are mounted in a recessed portion of the door frame 48 in which this metal frame 30 and cross members 31 and 32 are positioned. These gears extend through slots in the back of the member 30 opening to the bottom of the panel grooves to engage rack teeth provided in the edges of the movable panels 35 and 36. These gears may be rotated as by a handle 49.

In this construction illustrated in Figs. 7 to 11 the lower cross member, which is of metal, is slotted to receive the various panels as above enumerated. These panels 33, 34, 35 and 36 may be assembled in the frame 30 subsequent to its being secured in the usual wood door frame 48 by simply inserting the same through the slots provided therefor in the bottom cross member 32.

The louvre panel may also be introduced through this lower cross member 32 by providing a sufficiently wide slot 50 to permit the louvres to pass thereinto. The grooves 130

for the louvre panel in the vertical side members 30 and in the cross member 31 may be of less width as they are only required to be of a width to permit the edge of the metal louvre panel 38 to ride therein as will be seen from Fig. 10. After these panels have been introduced to position through the slots provided therefor in the lower cross member 32 a plate 51 may be secured to the bottom edge of the member 32 to provide a stop for the panels and prevent their moving downwardly through the slots. This plate 51 may be secured to the cross member 32 as by means of screws not here shown.

From the foregoing description it appears evident that by my improved construction I may change any ordinary wood door to a combination door by simply removing the panels between the stiles of the door and the lower cross member and introducing into the door frame thus provided a metal frame either of hollow form as shown in Figs. 1 to 6 or of the solid grooved form shown in Figs. 7 to 11 and thereupon the door may be used as a paneled door by the positioning of the imperforate movable panel members to close the opening provided in the upper part of the door or to withdraw the same to between the stationary panels of the lower part of the door thus providing a screen door by reason of the stationary screen being fixedly positioned covering approximately the upper half of the door. Also, by means of the manually movable louvre panel I am able to provide ventilation without exposing the interior of the rooms to view.

Having thus fully described my invention, what I claim is—

1. The combination with the frame of a door, of an insertible frame secured therewithin, a pair of oppositely positioned stationary panels covering the lower portion of the insertible frame, a pair of panels movable in the insertible frame to position to cover the upper portion thereof or to position between the lower stationary panels, and a screen member fixed in position covering the upper portion of the insertible frame and intermediate the movable panels.

2. The combination with the frame of a door, of an insertible metal frame secured thereto, the vertical side and top member thereof being provided with channels, a pair of stationary panels covering the opposite sides of the lower portion of the insertible frame, a pair of sliding panels movable in the channels of the frame to position to cover the upper portion of the insertible frame or retracted to between the stationary panels, and a screen member fixed in position covering the upper portion of the insertible frame intermediate the movable panels.

3. The combination with a frame of a door, of an insertible rectangular frame secured therewithin, a pair of oppositely positioned

stationary panels covering the lower portion of the insertible frame, a pair of panels movable in the insertible frame to position to cover the upper portion thereof or to position between the lower stationary panels, a flange extending inwardly from the upper portion of the side members of the insertible frame and from the upper cross member thereof, a screen member detachably secured to the said flange, the flange and the screen member occupying a position between the movable panels when in the raised position, and means for simultaneously moving the movable panels to a position closing the upper portion of the insertible frame or to retract the same to between the stationary panels.

4. The combination with the frame of a door, of an insertible metal frame secured thereto, a pair of oppositely positioned stationary panels covering the opposite sides of the lower portion of the insertible frame, a pair of panels movably supported in the insertible frame adapted to be moved to position covering the upper portion of the insertible frame or retracted to between the stationary panels, a fixed screen member extending across the upper portion of the insertible frame and occupying a position intermediate the movable panels, and a third movable panel having louvres adapted to be positioned either covering the upper portion of the insertible frame or to position between the stationary panels.

5. The combination with the frame of a door, of an insertible metal frame secured thereto, a pair of oppositely positioned stationary panels covering the lower portion of the insertible frame, a pair of panels movable in the frame to position the same in the upper portion of the frame or between the lower stationary panels, a manually operable means for moving the movable panels simultaneously, and a screen member fixed in position covering the upper portion of the insertible frame and intermediate the path of movement of the movable panels.

6. The combination with a frame of a door, of an insertible rectangular metal frame secured thereto, the side members and upper cross member being provided with grooves and the lower cross member having slots therethrough corresponding in position to the plane of the grooves, a series of panels insertible into the frame through the said slots, the said series of panels consisting of two panels adapted for stationary position on opposite sides of the lower portion of the inserted frame, a pair of panels movable longitudinally of the frame to cover the upper portion thereof or to position between the stationary panels, a movable panel having louvres manually movable to cover the upper portion of the frame or to position between the stationary panels, a screen member fixed

in position covering the upper portion of the inserted frame and occupying a position between the paths of movement of the movable panels and at one side of the louvred panel,
5 a pair of gears rotatably supported at one side of a vertical member of the metal frame extending through the slots provided therefor in the metal frame opening into grooves for the movable panels, racks provided in the
10 edges of the respective movable panels to engage the respective gears, and an operating handle for rotating the gears.

In testimony whereof, I sign this specification.
